(57) **CLAIM**

I claim the design for an overhead storage shelf, as shown and described.

DESCRIPTION

FIG. 1 is a front and side elevational perspective view of the overhead storage shelf;

FIG. 2 is a top plan view of the overhead storage shelf;

FIG. 3 is a bottom view of the overhead storage shelf;

FIG. 4 is a front view of the overhead storage shelf;

FIG. 5 is a rear view of the overhead storage shelf;

FIG. 6 is a right side elevational view of the overhead storage shelf; and,

FIG. 7 is a left side elevational view of the overhead storage shelf.
